UNITED STATES PATENT OFFICE.

MILNER HURD, OF SHEFFIELD, ENGLAND.

SCREEN FOR CINEMATOGRAPH PICTURES AND THE LIKE.

1,411,661.

Specification of Letters Patent. Patented Apr. 4, 1922.

Application filed March 19, 1920. Serial No. 367,065.

To all whom it may concern:

Be it known that I, MILNER HURD, a subject of the King of Great Britain and Ireland, residing at Sheffield, in the county of 5 York, England, have invented new and useful Improvements in Screens for Cinematograph Pictures and the like, of which the following is a specification.

My invention relates to improvements in 10 screens for cinematograph pictures and the like, and has for its object to show the pictures thrown on such screens in colours and to give them a beautifully soft and velvety appearance instead of the somewhat harsh 15 and monotonous black and white reproductions shown on the present types of screens, and to this end my invention consists in the provision of a screen made from a "pile" fabric with a single or multicoloured reflecting 20 surface, which may either be fixed or travel over rollers.

My invention will be better understood on reference to the accompanying sheet of drawings in which:—

25 Fig. 1 is a side elevation of a roller screen made according to my invention.

Fig. 2 is a front elevation of same.

Fig. 3 is a side elevation showing the character of the fabric I employ.

30 The same letters refer to similar parts throughout the several views.

In a screen made according to my invention, as shown in Figs. 1 and 2 two or more rollers *a* and *b* mounted on a wooden or 35 metal frame *c* carry a screen *d* made from a textile material like velvet, fustain, velvet cord or chenille, which has what is known as a "pile" surface, that is to say, it is essential that some fibres of the material shall 40 stand out perpendicularly about at right angles to the web of the material, as shown in Fig. 3 so that when a picture is projected on the screen a beautifully soft and deep velvety appearance shall be given to the picture.

45 My improved screen *d* may be in the form of an endless band, and may be made entirely of white material or of one or more coloured pieces or cords of material sewn together in consecutive order, such for example, white, blue, red yellow, violet, green and orange, any one coloured part acting as the screen for the time being, as indicated by the portions marked, 1, 2, 3 and 4 in Fig. 1, 50 which represent different coloured lengths of material, and by revolving the rollers the

colours may be changed to suit the character of the picture, for instance, if it is sylvan scenery that is being shown, the green portion of the screen forms a very appropriate 60 reflecting surface, the blue portion for a sea-scape, and so on.

I provide suitable gear such as the motor *e* (Fig. 2) for turning the required coloured portion into position intermittently, or I 65 may provide a continuous turning movement to bring all the colours into play in succession, thereby giving a pleasing change of colour to the picture in place of the monotonous black and white.

70 Alternatively, I sometimes make the screen of various pieces of coloured velvet or fustian, velvet cord or chenille sewn together, so that two or more colours shall be visible in the picture at the same time.

75 As an alternative to the above, I may use a fabric all white and put on it any desired colours by means of an air-brush, the various colours being thus beautifully shaded and merged into each other.

80 To conserve light, and to obtain delicate colour effects, I sometimes back the fabric with tin-foil or similar substances, coloured or plain, so that no light from the lantern is allowed to pass through the screen to deaden 85 the brilliancy of the picture, and the reflected light from the plain or coloured tin-foil backing, gives the desired colour effects.

85 The screen, if on rollers may be moved by hand by an attendant, or it may have an electric motor attached to it, worked by the lantern operator or his assistant.

90 To present a good flat surface to the light rays, and to conserve light, I sometimes provide, between the top and bottom rollers a 95 suitable solid or trellis work wood (or other suitable material) backing *f* to support large area screens, and I cover the surface with tin-foil instead of the back of the fabric, in this way I prevent distortion of the picture 100 due to the screen being bulged in or out, or waved by the wind, and also conserve light.

105 Having now described my invention, what I claim and desire to secure by Letters Patent is:—

1. A screen for cinematograph pictures and the like, comprising a web, and a non-transparent "pile" surface on said web, the fibers of said pile standing out approximately at right angles to said web.

110 2. Screens for cinematograph pictures and the like, having a "pile" surface fabric

backed with tin-foil, substantially as herein described.

3. Screens for cinematograph pictures and the like, having a surface of pile fabric, and 5 an independent rigid backing for said fabric the surface of said backing in proximity to the pile surface farbric being covered with tin-foil, substantially as herein described.

4. A screen for cinematograph pictures 10 and the like, comprising a web, and a non-transparent "pile" surface on said web, the

fibers of said pile standing out approximately at right-angles to said web portions of said pile surface being of different colors.

5. A screen for cinematograph pictures 15 and the like, comprising a web, and a "pile" surface on said web, said pile surface being divided into panels of different colors.

In testimony whereof I have signed my name to this specification.

MILNER HURD.
